US00D988361S

(12) **United States Design Patent** (10) Patent No.: **US D988,361 S**
Farlow et al. (45) Date of Patent: **** Jun. 6, 2023**

(54) **DISPLAY SCREEN WITH GRAPHICAL USER INTERFACE FOR SURGEON CONSOLE FOOT PEDALS**

(71) Applicant: **Covidien LP**, Mansfield, MA (US)

(72) Inventors: **Jared N. Farlow**, Los Angeles, CA (US); **Robert J. Stephens**, Superior, CO (US); **Elizabeth Lauren Lu**, Somerville, MA (US); **Edbert C. Wang**, Long Island City, NY (US); **Margaret A. Jacobi**, Waban, MA (US); **Sonya H. Mead**, Newton, MA (US); **Tara M. Kovalik**, Arlington, MA (US)

(73) Assignee: **Covidien LP**, Mansfield, MA (US)

(**) Term: **15 Years**

(21) Appl. No.: **29/804,269**

(22) Filed: **Aug. 19, 2021**

(57) **CLAIM**

The ornamental design for a display screen with graphical user interface for surgeon console foot pedals, substantially as shown and described.

DESCRIPTION

The FIGURE is a front view of a display screen with graphical user interface for surgeon console foot pedals. The broken lines showing the display screen form no part of the claimed design. The remaining broken lines showing portions of the graphical user interface form no part of the claimed design.

1 Claim, 1 Drawing Sheet
